SANDING MACHINE

Frans O. Albertson, Sioux City, Iowa, assignor to
 Albertson & Company, Inc., Sioux City, Iowa,
 a corporation of Iowa

Application August 13, 1937, Serial No. 158,857

2 Claims. (Cl. 51—170)

The present invention relates to sanding machines, and is particularly concerned with a sanding machine of the type comprising an electric motor, speed reduction gearing and a rotatable sanding disc, in which provision has been made for more than one definite range of speed.

In such sanding machines the speed is ordinarily determined by the power of the motor, the gearing and the load which is put upon the sanding disk, and for any given machine there is a proper load pressure which results in the best operation.

It is, however, desirable to have a machine which will operate at two different normal speeds, and one of the objects of the invention is the provision of an improved sanding machine which is provided with a gear reduction arrangement adapted to effect a change of speed of the sanding disc.

Another object of the invention is the provision of an improved sanding machine of the class described in which the speed of rotation of the sanding wheel may be changed by changing the gear ratio of the reduction gearing which is interposed between the motor and sanding machine.

Another object of the invention is the provision of an improved arrangement of the class described, which is also adapted to be used upon polishing machines so that a relatively low speed may be used when the initial rubbing of the wax is made, and a high speed may be used when the job is finally polished off.

Other objects and advantages of the invention will be apparent from the following description and accompanying drawings in which similar characters of reference indicate similar parts throughout the several views.

Referring to the drawings, of which there are two sheets:

Fig. 1 is a top plan view of a sanding machine with the disc disposed downwardly embodying the invention with a part of the housing broken away to show the speed changing gears;

Fig. 2 is a side elevational view of the sanding machine;

Fig. 3 is a vertical sectional view taken on the plane of the line 3—3 of Fig. 1 looking in the direction of the arrows showing the details of construction of the speed reduction gearing; and

Fig. 4 is a sectional view taken on the plane of the line 4—4 of Fig. 3 looking in the direction of the arrows.

The sanding machine preferably comprises an electric motor 10 provided with a speed reduction gearing located in housing 11 and controlled by

means of an electric switch located in housing 12. The foregoing elements are preferably located in line with each other and with a handle 13 through which the electric connection cord 14 extends.

The motor housing 10 is closed at one end with a cover plate 15, which is provided with bearing means for the motor drive shaft 16, which is provided at its end with a pinion 17.

The gear housing 11 and cover plate 15 rotatably support a stub shaft 18 (Fig. 4), to which is keyed a gear 19 which meshes with the pinion 17 as shown in Figs. 3 and 4. The gear observed in Fig. 4 below the pinion 17 does not mesh with it as it appears, because they are in different planes.

The stub shaft 18 is provided with two gears 20 and 21, which are non-rotatably but slidably mounted on the stub shaft 18 by means of a sliding key and keyway 22. Gears 20, 21 may be fastened together, and the gear 20 is provided on its left-hand face with a hub 23 having a peripherally extending slot 24 for receiving a yoke 25. The yoke 25 comprises a metal member having a pair of spaced arms 26, 27, one on each side of shaft 18, and yoke 25 is fixedly mounted on a push rod 28, which is slidably mounted in a bore 29.

The gear housing 11 has a slot at 30 to accommodate the push rod and its thumb piece 31, which is fixedly secured to the end of the push rod by means of a screw bolt 32. One may thus take hold of the push button 31 and cause the rod 28 to slide to the left or right to change the position of the gears 20, 21.

In Fig. 3 the push rod and gear 20 is at the extreme left position. The gear housing 11 also rotatably supports a second stub shaft 33 which is rotatably mounted in bearings 34, 35 in the gear housing and cover plate 15. This stub shaft fixedly supports a pair of gears, such as the pinion 36 and spur gear 37, and the pinion 36 is of such size that it meshes with the gear 20. The spur gear 37 is of such size and is so located that it meshes with the gear 21 when the gear 21 is brought into the proper plane by means of the push rod 28.

As the pinion 36 and gear 20 present a different gear ratio from that of the spur gear 37 and gear 21, it is possible to change the speed at which the stub shaft 33 is driven by the motor 10. The stub shaft 33 carries a pinion 38 which is adapted to mesh with a crown gear 39 carried by the spindle 40. The spindle 40 is rotatably mounted at its upper end upon a ball bearing 41 located in a socket in the gear housing 11, and at its lower end upon a ball bearing 42 which is mounted in a socket in the cover plate 43.

Cover plate 43 closes the open end of a gear housing 11 and is secured in place by a plurality of screw bolts 44. It preferably has an enlarged bore 45 surrounding the spindle for receiving the oil seal 46, which comprises a hat leather 47, a garter spring 48 and an oil seal housing 49. The garter spring 48 draws the leather 47 into engagement with the cylindrical portion 50 of spindle 40. At its outer end spindle 40 has an enlarged annular flange 51, which is provided with a plurality of apertures 52.

A pivoted lever 53 is mounted on the gear housing 11 and has a pin 54 which may be moved into any one of the apertures 52 to secure the spindle 40 in fixed position. At its outer end the spindle 40 is also provided with a reduced threaded portion 55 which is adapted to be received in the complementary threaded bore 56 of the hub 57 of a sanding wheel 58.

20 The sanding wheel usually comprises a sheet metal backing 59 to which is riveted or otherwise fixedly secured a rubber disc 60 having secured upon it a polishing bonnet or a sanding disc 61. By means of the gear shifting arrangement controlled with the thumb button 31, it is possible to rotate the sanding disc 61 at two different speeds. Relatively fast rotation may be secured for certain sanding operations, and a slower and more powerful action may be secured for other operations.

30 It will thus be observed that I have invented an improved sanding machine having a two speed gear arrangement; the ratio of the speed reduction gearing being used may be very quickly changed by merely reciprocating the push rod 28. Push rod 28 is held in either of its two positions by means of a spring-pressed ball 62 which is mounted in a bore 63 and engaged by a spring 64 reacting against a screw plug 65.

40 While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I

claim as new and desire to secure by Letters Patent of the United States, is:

1. In an electric sanding and polishing machine, the combination of an electric motor having a drive shaft and housing, with a gear housing carried by said motor housing, speed reduction gearing located in said gear housing, a drive spindle rotatably mounted in said gear housing and projecting therefrom, said drive spindle being operatively connected to said motor through said speed reduction gearing, and said drive spindle having a threaded portion, a sanding wheel having a hub provided with a complementary threaded portion, said sanding wheel being adapted to support operating tools, a thrust collar carried by said drive spindle, said thrust collar being provided with a radially extending socket, and a pivoted lever carried by said gear housing, said pivoted lever being mounted in a pivot extending substantially parallel to said drive spindle, and having a transversely extending cylindrical lug adapted to be received in said socket whereby the spindle may be secured and held in fixed position by means of said pivoted lever, while the sanding wheel is threaded on or off the threaded portion of said drive spindle.

2. In an electric sanding and polishing machine, the combination of an electric motor having a drive shaft and housing, with a gear housing carried by said motor housing, gearing located in said gear housing, a drive spindle rotatably mounted in said gear housing, said drive spindle being operatively connected to said motor through said gearing, and said drive spindle having a threaded portion, an operating tool carried by a complementary threaded member mounted on said drive spindle, said member being provided with an inwardly extending socket, and a pivoted lever carried by said gear housing, said pivoted lever being mounted in a pivot extending substantially parallel to said drive spindle, and having a transversely extending lug adapted to be received in said socket whereby the spindle may be secured and held in fixed position by means of said pivoted lever, while the sanding wheel is threaded on or off the threaded portion of said drive spindle.

FRANS O. ALBERTSON.
